DESIGN FOR A VENTED POURING SPOUT FOR CONTAINER

Frank R. Ruther, Whittier, Calif.

Application October 1, 1943, Serial No. 111,247

Term of patent 14 years

To all whom it may concern:

Be it known that I, Frank R. Ruther, a citizen of the United States, residing at Whittier, in the county of Los Angeles and State of California, have invented a new, original, and ornamental Design for a Vented Pouring Spout for Container, of which the following is a specification, reference being had to the accompanying drawing, forming a part thereof.

In the accompanying drawing:

Fig. 1 is a top plan view of a vented pouring spout for container showing my new design;

Fig. 2 is a side elevational view;

Fig. 3 is a front view, and

Fig. 4 is a fragmentary sectional view taken on line 4—4, Fig. 1.

I claim:

The ornamental design for a vented pouring spout for container, as shown.

FRANK R. RUTHER.
